UNITED STATES PATENT OFFICE

138,687

DESIGN FOR A BAR OF SOAP

William G. Werner and Charles T. Gerhart, Cincinnati, Ohio, assignors to The Procter & Gamble Company, Cincinnati, Ohio, a corporation of Ohio

Application April 25, 1942, Serial No. 106,703

Term of patent 14 years

(Cl. D73—1)

To all whom it may concern:

Be it known that we, William G. Werner and Charles T. Gerhart, citizens of the United States, and both residents of Cincinnati, in the county of Hamilton and State of Ohio, have invented a new, original, and ornamental Design for a Bar of Soap, of which the following is a specification, reference being had to the accompanying drawing, forming a part thereof.

In the drawing:

Figure 1 is a top plan view of a bar of soap, showing our new design;

Figure 2 is a front elevational view of the same;

Figure 3 is an end elevational view of the same; and

Figure 4 is a bottom view of the same in per-

spective, the left hand portion of the bar shown in this view being the right hand portion of the bar shown in Figure 1.

The design consists of the shape of the bar having relative proportions of the several dimensions as shown, the division line dividing it into two parts, and the presence of a panel across each part containing on each face the brand name on one section and producer's name on the other, this condition being reversed on the other face of the bar.

We claim:

The ornamental design for a bar of soap, substantially as shown and described.

WILLIAM G. WERNER.
CHARLES T. GERHART.
